UNITED STATES PATENT OFFICE.

EMANUEL AUFIERO, OF BROOKLYN, NEW YORK.

MECHANICAL HORN.

1,239,426.

Specification of Letters Patent.

Patented Sept. 4, 1917.

Application filed October 12, 1915. Serial No. 55,385.

To all whom it may concern:

Be it known that I, EMANUEL AUFIERO, a citizen of the United States, and a resident of the borough of Brooklyn, Kings county, New York, have invented new and useful Improvements in Mechanical Horns, of which the following is a specification.

This invention relates to mechanical horns of the character used for warning signals for automobiles, motorcycles, and other vehicles, and has for its object to provide a horn of this character of simple construction, containing a minimum number of working parts, and designed to be of exceedingly cheap manufacture without sacrificing any of the advantages of durability, appearances, and ease of operation.

In the accompanying drawings, I have illustrated two different modifications of my improved horn and in said drawings

Figures 1 and 2 are longitudinal and transverse sections respectively through a mechanical horn embodying one form of my said invention,

Fig. 3 is a section on line 3—3 of Fig. 1; and

Fig. 4 is a longitudinal sectional view illustrating the alternate form of my invention.

Similar reference characters indicate similar parts throughout the several views.

My improved horn comprises the usual cylindrical casing 1 having one end closed by the vibratory diaphragm 2 held in place by the clamping ring 3 in the usual manner. The diaphragm 2 is provided at its center with a contact pin 4 which is adapted to be engaged by the serrated disk 5 mounted in the casing on a transverse shaft 6 extending across the casing in a plane parallel to the plane of the diaphragm and revolvably supported on screw 7 set in the sides of the casing. The shaft 6 has formed integrally with it a pinion 8 adjacent one side of the disk 5, while attached to the disk on its opposite face are a plurality of sheet metal disks 9 constituting a fly wheel for increasing the momentum of the disk when actuated in the manner to be hereinafter described.

Attached to the shaft 6 adjacent the outer disk 9 is a ratchet wheel 10 adapted to be engaged by a pawl 11 pivoted on the face of the adjacent disk 9, whereby the rotation of the shaft in one direction will operate to rotate the serrated disk, while in the other direction it will be free of the disk.

For operating the shaft 6 I preferably provide a rack bar 12 mounted for reciprocation in a direction at right angles to the shaft and as shown in the drawing in a plane parallel to the plane of the diaphragm. The rack bar is preferably supported in the manner shown in Figs. 1 and 2 in a guide sleeve 13 whose ends project through the wall of the casing and are firmly soldered or otherwise attached in place. One end of the sleeve 13 is closed, as shown, to provide a seat for the coil spring 14 working in the longitudinal hole or groove in the end of the rack bar to return the rack bar to its opposite or elevated position when depressed by means of the knob 15 on the outer end of the rack bar.

The side of the sleeve 13 adjacent the pinion 8 is cut away as illustrated to permit the teeth of the rack bar to engage the pinion.

The operation of the device is obvious from the above description. By weighting the serrated disk in the manner illustrated it may be given sufficient momentum upon the downward movement of the rack for it to continue its rotation against the resistance of the contact pin 4 during the upward movement of the rack under the action of the spring whereby continued vibration of the diaphragm may be produced by the reciprocation of the rack bar. By projecting the rack through the lower side of the casing I am able to give the shaft a greater number of rotations at each reciprocation, thereby more certainly insuring its continued rotation during the idle movement of the rack bar. The guide sleeve serves to preserve the alinement of the pinion and rack with consequent ease of operation and permits a thinner shell to be employed for the casing without weakening the construction. The casing, guide sleeve, diaphragm, and disks are by my improved construction all made of sheet metal whereby the cost of construction is materially reduced.

In the modified construction shown in Fig. 3 all parts are of substantially the same construction as in the preferred type except that the spring for returning the rack bar instead of being arranged in the end of the bar is mounted on a rod 20 set in the casing to the rear of the rack bar and parallel therewith, the spring 21 occupying the full width of the casing and operating the rack bar through means of a lug or bracket

22 attached to the rear of the rack bar and sliding on the rod 20. This construction provides an additional guide for the spring and rack but is somewhat more costly to 5 manufacture than the preferred construction.

In the foregoing specification and accompanying drawing I have described and shown my improved horn in all its details 10 of construction. It is to be understood, however, that the invention is not limited to such details, but that they may be variously modified without departing from the spirit of the invention or the scope of the appended claims.

Having thus described my invention what I claim and desire to secure by Letters Patent is:

1. In a mechanical horn the combination 20 of a vibratory diaphragm, a casing having one end closed by said diaphragm, a heavy serrated disk supported within said casing for rotation about an axis parallel with the plane of said diaphragm, a pinion supported 25 within the casing adjacent said disk for rotation about the same axis, a guide sleeve extending across the casing and projecting beyond its wall, a toothed rack mounted for reciprocation in said guide sleeve, said guide 30 sleeve having a portion cut away adjacent the said pinion to permit the engagement of the rack teeth therewith and a one way clutch connection for transmitting motion from said pinion to said disk.

35 2. In a mechanical horn the combination of a vibratory diaphragm, a casing having one end closed by said diaphragm, a heavy serrated disk supported within said casing for rotation about an axis parallel with the 40 plane of said diaphragm, a pinion supported within the casing adjacent said disk for rotation about the same axis, a guide sleeve extending across the casing and projecting beyond its wall, a toothed rack mounted for 45 reciprocation in said guide sleeve, said guide sleeve having a portion cut away adjacent the said pinion to permit the engagement of the rack teeth therewith, a one way clutch connection for transmitting motion from 50 said pinion to said disk, a spring having operative engagement with said rack for maintaining it projected beyond the guide sleeve a predetermined extent, and a knob on said rack whereby it may be directly 55 operated.

60 3. In a mechanical horn the combination of a casing, a vibratory diaphragm closing one end of the casing, a shaft extending across said casing, a disk for vibrating said diaphragm, said disk having radial serrations on its periphery to operatively engage said diaphragm, a pinion on said shaft, a tubular guide extending across said casing at right angles to said shaft and projecting 65 beyond the wall of said casing, a toothed

rack mounted for reciprocation in said guideway with its teeth in engagement with said pinion, a spring in said guideway and engaging said rack for maintaining it normally projected to a predetermined position 70 beyond said guideway, and a one way clutch between said pinion and said disk for converting the oscillating motion of the pinion into continuous rotary motion of the disk.

4. In a mechanical horn the combination 75 of a sheet metal casing having an outwardly turned flange at one end, a vibratory diaphragm supported by said flange and of larger diameter than the casing, said diaphragm having a contact wear-piece, a disk supported in said casing for rotation about an axis substantially parallel with the plane 80 of the diaphragm, said disk having peripheral serrations adapted to engage said wear-piece to vibrate the diaphragm, a tubular guide supported by the cylindrical wall of said casing and extending across the casing at right angles to the axis of rotation of said disk, a pinion supported in said casing adjacent said disk for rotation about 85 the same axis, said tubular guide having its wall adjacent the teeth of said pinion cut away with the teeth of the pinion projecting into the guide, a toothed rack mounted for reciprocation in the guide with its teeth 90 in engagement with the pinion, a spring for maintaining the rack projecting out of the guide with the teeth at its end in engagement with the pinion, the toothed portion 95 of said rack being of such length that the teeth project beyond the cylindrical wall of the casing but not beyond the end of the guide, and a one way clutch for transmitting motion from the pinion to the disk in one direction of its oscillating motion.

100 5. In a mechanical horn the combination 105 of a sheet metal casing having an outwardly turned flange at one end, a vibratory diaphragm supported by said flange and of larger diameter than the casing, said diaphragm having a contact wear-piece, a disk supported in said casing for rotation about an axis substantially parallel with the plane 110 of the diaphragm, said disk having peripheral serrations adapted to engage said wear-piece to vibrate the diaphragm, a tubular guide supported by the cylindrical wall of said casing and extending across the casing at right angles to the axis of rotation of said disk, a pinion supported in said casing 115 adjacent said disk for rotation about the same axis, said tubular guide having its wall adjacent the teeth of said pinion cut away with the teeth of the pinion projecting into the guide, a toothed rack mounted for reciprocation in the guide with its teeth in engagement with the pinion, said rack having a longitudinal recess back of said teeth, a spring in said recess for maintaining the rack projecting out of the guide with the 120 teeth 125 in engagement with the pinion, a spring in said recess for maintaining the rack projecting out of the guide with the 130 teeth.

teeth at its end in engagement with the pinion, the toothed portion of said rack being of such length that the teeth project beyond the cylindrical wall of the casing but not beyond the end of the guide, and a one way clutch for transmitting motion from the pinion to the disk in one direction of its oscillating motion.

Signed at New York in the county of New York and State of New York this 13th ¹⁰ day of September, 1915.

EMANUEL AUFIERO.
